W. RAHE

AUTOMOBILE BUMPER

Filed Sept. 29, 1926

INVENTOR.

BY

William Rahe
Allen & Allen

ATTORNEY.

Patented May 24, 1927.

UNITED STATES PATENT OFFICE.

WILLIAM RAHE, OF CINCINNATI, OHIO.

AUTOMOBILE BUMPER.

Application filed September 29, 1926. Serial No. 138,505.

My invention relates to automobile bumpers of the tubular type and particularly to the cap construction of the ends of the tubes.

It is the object of my invention to provide a construction for the ends of the tubular elements of bumpers which although of light, inexpensive construction will be very resistant to the blows which the bumpers are built to resist.

In the art, it is quite common for manufacturers of bumpers to provide bumpers having tubular abutment elements extending laterally across the automobile frame. It is also quite common to provide caps for the ends of the tubular pieces which will protect what would otherwise be the open ends of the tubes. In order to have sufficient strength to resist end shocks, these caps have been made with sleeve-like portions adapted to be driven over the ends of the tubes. Ordinarily the rounded portions which have closed the ends of the sleeves and extended laterally across the openings in the tubes have been of heavy metal. This has necessitated having the caps cast, and then finished. When light caps such as could be stamped or pressed out of metal have been used, they have not been found to be sufficiently strong to stand the blows to which they are subjected. The heavy cast caps have been found too expensive for practical use particularly as a set of bumpers requires as many as a dozen caps.

It is my object to provide a stiff metal disc preferably of rounded reinforced contour in accordance with the shape of the cap, which will form a driving fit within the cap, and which will abut the edges of the tubes thereby strengthening the resisting power of the cap toward a collapsing strain or blow. My invention has enabled me to use light metal such as aluminum for the caps which metal may be stamped or pressed into shape with a die, and the provision of discs of metal such as steel has enabled me to make more durable caps at very materially less cost.

Referring to the drawings in which I have illustrated several preferred structures illustrating my invention—

Figure 1 shows in section the end of a tubular bumper rail having a cap with a convex base.

Figure 2 shows in section the end of a tubular bumper rail having a cap with a concave base.

Figure 3 is a plan view of a different type of reinforcing disc than the types shown in Figures 1 and 2.

Figure 4 shows in plan still another type of reinforcing disc.

Figure 5 is a section along the line 5—5 in Figure 3.

Figure 6 is a section along the line 6—6 in Figure 4.

Figure 7 is a section along the line 7—7 in Figure 4.

The tubular rail of the bumper is indicated at 1. The caps generally indicated at 2 have sleeve like portions 3 which engage the outer peripheries of the tubular rails, or bars, and driven preferably with a driving fit within the caps are the reinforcing discs 4. It will be noted that Figure 1 shows a cap with a convex base while Figure 2 shows a cap with a concave base. In combination with the cap, shown in Figure 1, I have illustrated a convex disc which abuts the inner portion of the base of the cap throughout its entire surface. Figure 2 on the other hand which has a concave cap has a flat disc which engages the inner face of the cap only at its center. Figures 3 and 5 show a disc of flat contour with cross-like corrugations 5 which reinforce the resistance of the disc to a collapsing blow. Figures 4, 6 and 7 show a convex disc of oval shape. There are many styles and shapes of inner disc which may be used to reinforce the base of the caps and although I have shown several preferred types, I do not wish because of the failure to show other types to be limited to the specific structures shown.

It will be within the realms of mechanical equivalency to vary the shape of the inner discs in accordance with the particular requirements of the type and shape of cap used. Although I prefer to make the caps of aluminum and the disc of steel, the metals may also be varied.

Having thus described my invention, what I claim as new and desire to secure by Letters Patent is:

1. In combination with a tubular element of a hollow bumper bar, a cap for fitting over the end of the tube, said cap having sleeve-like portions for engaging the outer surface of the tubular element, and a disc of equivalent diameter to the inner diameter of said sleeve-like portions, said disc adapted to reinforce the cap against a collapsing strain.

2. In combination with a tubular element of a hollow bumper bar, a cap for fitting over the end of the tube, said cap having sleeve-like portions for engaging the outer surface of the tubular element, and a disc of equivalent diameter to the inner diameter of said sleeve-like portions, said disc adapted to reinforce the cap against a collapsing strain, said disc bearing against the inner surface of said cap.
3. In combination with a tubular element of a hollow bumper bar, a cap having portions adapted to engage the outer surface of the tubular element adjacent its open end, a reinforcing disc adapted to be driven within said cap and to be moved with the en-

gagement of the cap on the tubular element into contact with the edges of the end of the tubular element.

4. In combination with a tubular element 20 of a hollow bumper bar, a cap having portions adapted to engage the outer surface of the tubular element adjacent its open end, a reinforcing disc adapted to be driven within said cap and to be moved with the 25 engagement of the cap on the tubular element into contact with the edges of the end of the tubular element, said disc having portions abutting the inner surface of the cap for the purposes described.

WILLIAM RAHE.
